UNITED STATES PATENT OFFICE.

THURE E. DAHL, OF NEW YORK, N. Y.

DESIGN FOR A PEDESTAL FOR LIGHTING FIXTURES.

Application filed June 9, 1922. Serial No. 2,600. Term of patent 3½ years.

To all whom it may concern:

Be it known that I, THURE E. DAHL, a subject of the King of Sweden, and residing at New York, in the county of New York and State of New York, have invented a new, original, and ornamental Design for a Pedestal for Lighting Fixtures, of which the following is a specification, reference being had to the accompanying drawing, forming part thereof.

Fig. 1 is a front view of a pedestal for lighting fixtures, showing my new design.

Fig. 2 is a plan view of half of the base looking down.

I claim:

The ornamental design for a pedestal for lighting fixtures, as shown.

THURE E. DAHL.
